US00D623855S

(12) **United States Design Patent**
Elliott et al.

(10) **Patent No.:** US D623,855 S
(45) **Date of Patent:** ** Sep. 21, 2010

(54) **ELECTRICALLY POWERED SUITCASE**

(76) Inventors: **Beverely J. Elliott**, 4511 N. Campbell Ave., #255, Tucson, AZ (US) 85718; **Robert Alan Elliott**, 4511 N. Campbell Ave., #255, Tucson, AZ (US) 85718

(**) Term: **14 Years**

(21) Appl. No.: **29/349,322**

(22) Filed: **Mar. 25, 2010**

(51) **LOC (9) Cl.** 03-01

(52) **U.S. Cl.** **D3/279**

(58) **Field of Classification Search** D3/272, D3/273, 274, 276, 279, 283, 289, 301, 318, D3/321, 323, 902, 904; 190/100, 108, 110, 190/111, 115, 122, 124, 126, 127; 280/37, 280/47.17, 47.19, 47.2, 47.24, 47.26, 47.315

See application file for complete search history.
